TOY SPRING SHOE

Kenneth V. Dobson, 3135 W. 1st Ave., Denver, Colo.

Filed Feb. 24, 1964, Ser. No. 78,752

Term of patent 7 years

(Cl. D34—14)

FIG. 1.

FIG. 2.

FIG. 3.

FIG. 4.

FIG. 5.

FIGURE 1 is a side elevational view of a toy spring shoe showing my new design, the side not shown being the same and the securing straps shown in broken lines for illustrative purposes only.

I claim:

The ornamental design for a toy spring shoe, as shown and described.
